REFRIGERATION

Sven W. E. Andersson, Evansville, Ind., assignor
to Servel, Inc., New York, N. Y., a corporation of
Delaware

Application October 19, 1937, Serial No. 169,789

4 Claims. (Cl. 236—80)

My invention relates to refrigeration, and more particularly to control of refrigeration apparatus. This application is a continuation in part of my application Serial No. 113,153, filed November 28, 1936.

It is an object of my invention to provide an improved control device for controlling the heat supply of refrigeration apparatus of the absorption type.

Another object of my invention is to provide an improved control device for refrigeration apparatus of the absorption type in which a valve is connected to a movable diaphragm and the device is so constructed and arranged that gas under pressure constantly exerts force on one side of the diaphragm and also exerts force on the other side of the diaphragm in response to a temperature whereby the diaphragm is operative to flex and effect control of the valve.

The novel features which I believe to be characteristic of my invention are set forth with particularity in the claims. The invention, both as to organization and method, together with further objects and advantages thereof, will be better understood by reference to the following description taken in connection with the accompanying drawings of which Fig. 1 diagrammatically illustrates refrigeration apparatus of an absorption type provided with a control device embodying my invention; Fig. 2 is an enlarged vertical sectional view of the control device shown in Fig. 1; and Fig. 3 is a fragmentary sectional view illustrating a modification of the device shown in Fig. 2.

Referring to Fig. 1, I have shown my improved control device in connection with absorption refrigeration apparatus of a uniform pressure type, generally as described in Patent No. 1,609,334 to von Platen and Munters, which contains an auxiliary pressure equalizing gas. The refrigeration apparatus comprises a generator 10 having a rear chamber 11 and a forward chamber 12 communicating with an upward extending standpipe or separator 13. The generator contains a body of absorption liquid, such as water, having a suitable refrigerant, such as ammonia, in solution therein. The generator 10 is heated by a gas burner 14 which projects its flame into the forward end of a horizontal flue 15 which extends through the generator. A suitable combustible gas is delivered from a source of supply through conduit 16, control device 17 which will be described hereinafter, and conduit 18 to the burner 14.

The heat applied to the generator 10 causes ammonia vapor and absorption liquid in chamber 11 to pass through an opening 19 in the lower end of a small vertical conduit 20 which constitutes a vapor-lift and conduits ammonia vapor and absorption liquid to the upper part of the stand-pipe 13. The liberated ammonia vapor entering the stand-pipe 13 from the conduit 20, as well as the ammonia vapor expelled from solution in stand-pipe 13 and chamber 12, flows upward through a conduit 21 and liquid-cooled rectifier 22 into a condenser 26 which is shown in the form of looped coil. The refrigerant is liquefied in the condenser 26 by a cooling medium, such as water, which circulates through a jacket 27 surrounding the condenser coil. The liquefied refrigerant flows from the condenser 26 to the rectifier 22 so that any water vapor which may accompany the ammonia vapor is condensed and drains back to the generator. A portion of the conduit 28 through which the cooling medium flows from the jacket 27 is arranged in thermal contact with the upper part of the conduit 21, as indicated at 29, also to effect condensation of any water vapor accompanying the ammonia vapor.

The liquefied ammonia flows from the rectifier 22 through a conduit 30 into the upper end of an evaporator or cooling unit 31 which is arranged in a thermally insulated storage compartment 32. An inert gas, such as hydrogen, enters the upper end of the evaporator 31 from the outer passage 33 of a gas heat exchanger 34. The liquid ammonia evaporates and diffuses into the hydrogen with consequent absorption of heat from the surroundings of the evaporator 31. The resulting mixture of ammonia and hydrogen, that is, gas rich in ammonia, flows downward from the evaporator 31 through the inner passage or conduit 35 of the gas heat exchanger 34 which is connected at its lower end to the lower end of an absorber 36. The ammonia vapor in the rich gas mixture is absorbed into weak absorption liquid that enters the upper part of the absorber 36 through a vertically extending conduit 37. The heat liberated with such absorption of ammonia vapor is transferred to a cooling medium, such as water, which flows upward within a coil 38 which surrounds the absorber 36 and is connected by conduit 39 to the lower end of the jacket 27.

The hydrogen, which is practically insoluble and weak in ammonia, flows upward from the absorber 36 through the outer passage 33 of the gas heat exchanger 34 and into the upper end

of the evaporator 31. The gas heat exchanger 34 transfers heat from gas which is weak in ammonia and flowing toward the evaporator 31 to gas which is rich in ammonia and flowing toward the absorber 36.

The absorption liquid flowing downward through the absorber 36 in counter-flow to the gas mixture becomes enriched in ammonia and flows through a conduit 40 and inner passage 41 of a liquid heat exchanger to chamber 11 of the generator 10. The liberated ammonia vapor and absorption liquid are caused to flow upward through the vertical conduit 20 into the upper part of the stand-pipe 13, as explained above, to a higher level than it is in the absorber 36, and the absorption liquid weak in ammonia flows from the chamber 12 through conduit 42, the outer passage 43 of the liquid heat exchanger, and conduit 37 into the upper end of the absorber 36.

The lower end of the condenser 26 is connected by a conduit 44, vessel 45, and conduit 46 to the gas circuit, so that any hydrogen which may pass through the condenser can flow to the gas circuit and not be trapped in the condenser. If ammonia is not liquefied in the condenser, due to changes in temperature of the cooling medium or the rate at which it flows through the condenser, for example, the ammonia vapor will flow through conduit 44 to displace hydrogen in the vessel 35 and force such hydrogen through conduit 46 into the gas circuit, thereby raising the total pressure in the system so that an adequate condensing pressure is obtained for the increased temperature of the condenser.

In accordance with my invention, the flow of gas to the burner 14 is controlled by the control device 17. Referring to Fig. 2, the control device 17 comprises a casing 47 having inlet and outlet openings 48 and 49 formed within bosses 50 and 51 to which are connected the conduits 16 and 18, respectively. A resilient or movable diaphragm 52 is secured at its peripheral edge between the two parts of the casing 47 to form an upper chamber 53 and a lower chamber 54, and in the lower chamber 54 is provided a partition 55 having an opening to form a main passage for flow of gas from the inlet 48 to the outlet 49.

To the partition 55 at the opening therein is secured a short sleeve member 56 which serves as a seat for a valve 57 having a stem 58 secured to the diaphragm 52. The valve 57 is provided with a recess to receive the threaded upper end of a stud 59 upon which is mounted washers or weights 60 and to the lower rounded end of which is secured a removable snap-on button or spring clamp 61.

The spring clamp 61 is adapted to bear against a thermal element arranged at the lower end of the casing 47. This thermal element comprises a resilient diaphragm 62 secured to the peripheral edge of a plate 63 which in turn is secured between the lower end of the casing 47 and a cover plate 64. At a central opening in the plate 64 is secured one end of a tube 65 which extends through an opening in the cover plate 64 and is connected at its other end to a thermal bulb 66 which is arranged in thermal contact with the liquid cooled rectifier 22, as shown in Fig. 1.

The resilient diaphragm 62 and plate 63, tube 65, and bulb 66 constitute an expansible fluid thermostat which contains a suitable volatile fluid that increases and decreases in volume with

corresponding changes in temperature. The resilient diaphragm 62 moves toward and away from the valve opening with an increase and decrease in volume of the volatile fluid, and these movements of the diaphragm 62 are utilized to regulate the valve 57 and control the flow of gas to the burner 14, as will be described hereinafter.

The upper part of the casing 47 is provided with a partition 67 which forms the extreme upper chamber 68 and, with the diaphragm 52, forms the intermediate chamber 53. The casing 47 is provided with a by-pass passage 69 to permit gas to enter the outer chamber 68 from the main gas passage formed by the lower chamber 54. The flow of gas from the chamber 68 through an opening in the partition 67 and into the chamber 53 is controlled by a valve 70 which is urged to its closed position by a resilient leaf spring 71 secured to the underside of the partition 67. The casing 47 is provided with an opening 72 communicating with chamber 53, and at this opening is secured a conduit 73 which terminates in the vicinity of the burner 14, as shown in Fig. 1.

The valve 70 is provided with a triangular-shaped stem 74 having an enlarged head 75 which is adapted to bear against a thermal element 76. This thermal element comprises an expansible diaphragm which is secured to and in open communication with a hollow hub member 77 to which is connected one end of a tube 78, the other end of which is connected to a thermal bulb 79 arranged in thermal contact with the evaporator 31, as shown in Fig. 1. The hub member 77 is mounted on a resilient diaphragm 80 which is secured at its peripheral edge between the upper end of the casing 47 and a cover plate 81 having an opening through which the tube 78 passes. The cover plate 81 is provided with an adjustment screw 82 for adjusting the position of the resilient diaphragm 80 and hence the position of the expansible diaphragm 76.

The expansible diaphragm 76, tube 78, and bulb 79 also constitute an expansible fluid thermostat which contains a suitable volatile fluid that increases and decreases in volume with corresponding changes of temperature. The expansible diaphragm 76 expands and contracts with an increase and decrease in volume of the volatile fluid, and these movements are transmitted to the valve 70 to control the flow of gas from the outer chamber 68 into the intermediate chamber 53.

The structure which is disposed in the chambers 53 and 68 and just described is capable of regulating valve 70 to effect control of the valve 57 and hence the flow of gas to the burner 14, so that the evaporator or cooling unit 31 of the refrigeration apparatus will be capable of maintaining the storage compartment 32 at a desired low temperature. When the evaporator 31 tends to rise above the desired low temperature, the volatile fluid of the expansible fluid thermostat increases in volume and causes the expansible diaphragm 76 to expand whereby the enlarged head 75 against which it bears is moved downward and causes the valve 70 to open against the action of the leaf spring 71. Under these conditions, gas flows from the chamber 68 or the main gas passage through the passage 69, chamber 68, and opening in the partition 67 into the chamber 53.

When the gas pressures in the chambers 53 and 54 are substantially the same and the forces exerted on the top and under sides of the diaphragm 52 are more or less equalized, the diaphragm 52 will move downward to its full open position due to weight of the valve 57 and the weights or washers 60 which may be referred to as a loading means on the diaphragm 52. With the valve 57 in its full open position, gas flows to the burner 14 at such a rate that the heat applied to the refrigeration apparatus is effective to heat refrigerant to its vaporization temperature or boiling point, so that refrigerant is vaporized and expelled out of solution from the absorption liquid. With the burner flame of such size that refrigerant is expelled out of solution from absorption liquid, the refrigeration apparatus operates in the manner described above to produce cold in the storage compartment 32. The gas flowing into the chamber 53 during the periods the valve 70 is open is conducted therefrom through conduit 73 to the vicinity of the burner 14 and augments the heating of the generator 10 effected by the burner.

When the evaporator 31 tends to fall below the desired low temperature, the volatile fluid of the expansible fluid thermostat becomes reduced in volume and causes the expansible diaphragm 76 to contract, whereby the resilient leaf spring 71 becomes effective to urge the valve 70 to its closed position. Under these conditions, the chamber 53 is substantially at atmospheric pressure and the pressure in the chamber 54 or main gas passage is the same as that in the gas supply conduit 18. Since the force now exerted on the under side of the diaphragm 52 is considerably greater than that exerted on the top side of the diaphragm, the resultant force exerted on the diaphragm will cause the latter to move upward and also move the valve toward its closed position. The load on the diaphragm 52 effected by the weights or washers 60 is preferably such that during normal operation valve 57 will not move to its completely closed position when valve 70 is closed, but will assume such a position that gas flows to the burner at a reduced rate whereby heat of liquid is supplied to the refrigerant and the refrigerant is heated to a temperature slightly below its vaporization temperature. Since refrigerant is not expelled out of absorption liquid under these conditions, cold is not produced in the storage compartment 32 by the evaporator 31.

When the evaporator 31 again tends to rise above the desired low temperature, the valve 70 is opened to vary the resultant force exerted on the diaphragm 52 and effect movement of the valve 57 toward its full open position, as described above. It will now be understood that the control device is so constructed and arranged that the gas under pressure in the chamber 54 or main gas passage constantly exerts force on one side of the diaphragm 52 and also exerts force on the other side of the diaphragm in response to change of temperature from a predetermined value to cause flexing of the diaphragm and hence control the valve 57.

The valve 57 controls the flow of gas to the burner 14 in response to the action of the thermal element 62 as well as the action of the thermal element 76. If for any reason the temperature of the liquid-cooled rectifier 22 becomes relatively high, due to failure of the cooling medium to circulate through the pipe 27 surrounding the condenser 26, for example, the volatile

fluid increases in volume and causes the resilient diaphragm 62 to expand and move upward. With such upward movement of the resilient diaphragm 62 the valve 57 is moved to its closed position irrespective of the resultant force exerted on the diaphragm by gas under pressure in the main passage or chamber 54. When the valve 57 is caused to move to its fully closed position in response to a predetermined rise of temperature, the supply of gas to the burner 14 is shut off completely, whereby heat is no longer applied to the refrigeration apparatus.

If desired, means other than weights or washers 60 may be employed to load the diaphragm 52 to adjust the rate of flow of gas to the burner during the periods when the burner is operating under a "minimum flame" condition. Further, a relatively small movement of the expansible diaphragm 76 to effect movement of the valve 70 produces a much greater movement of the movable diaphragm 52 and main valve 57 connected thereto, so that a sensitive control of the flow of gas to burner 14 is obtained.

When valve 70 is closed, gas is delivered to burner 14 at a minimum pressure with valve 57 in its uppermost position. The force exerted by gas on the under side of diaphragm 52 is balanced by atmospheric force on the upper side thereof and the total weight on the diaphragm including valve 57 and the loading means 60. With any changes in gas line pressure, the control device 17 under these conditions acts as a pressure regulator to maintain the minimum gas delivery pressure substantially constant. When the gas line pressure at inlet 48 increases, for example, the gas pressure in chamber 54 tends to increase and move diaphragm 52 and valve 57 upward, whereby the flow of gas past valve 57 is reduced. The valve 57 assumes a new position for the increased gas line pressure when the forces exerted on opposite sides of diaphragm 52 are balanced. In this new position of valve 57 the gas pressure on the under side of diaphragm 52 is the same as it was before an increase in gas line pressure took place, whereby gas is delivered to burner 14 at the same minimum gas delivery pressure.

Similarly, when the gas line pressure decreases at inlet 48, the gas pressure on the under side of diaphragm 52 tends to decrease so that the diaphragm and valve 57 move downward and the flow of gas past valve 57 is increased. The valve 57 assumes a new position for the reduced gas line pressure when the forces exerted on opposite sides of the diaphragm are again balanced. In this new position of valve 57 the gas pressure in chamber 54 is again the same as it was before a reduction in gas line pressure took place, whereby gas is delivered to burner 14 substantially at the same minimum gas pressure.

The above gas pressure regulation also occurs whenever valve 70 is not fully open and the latter effects a pressure differential. In other words, whenever valve 70 is not fully open and the gas pressure in chamber 53 is less than that in chamber 54, valve 57 is capable of moving toward and away from its closed position with changes in gas line pressure to maintain the gas delivery pressure substantially constant for each particular position that thermal element 76 causes valve 57 to assume.

The above described gas pressure regulation is possible when valve 70 is closed, or only partly open and effects a pressure differential, because diaphragm 52 is capable of moving valve 57

toward its closed position when the gas line pressure increases. When valve 70 is fully open, however, no pressure differential is effected between chambers 53 and 54 with valve 57 fully open. With valve 57 fully open and gas being delivered to burner 14 at maximum pressure, therefore, no gas pressure regulation occurs because the gas pressures on opposite sides of diaphragm 52 will always remain substantially the same irrespective of changes in gas line pressure.

In Fig. 3 I have shown a modification of the control device 17 of Fig. 2 whereby the maximum pressure at which gas is delivered to burner 14 may be maintained substantially constant even when valve 70 is fully open. In this modification the by-pass passage 69a connecting chambers 53 and 54 corresponds to the by-pass passage 69 in Fig. 2. The flow of gas in passage 69a is controlled by a valve 83 having a threaded screw head 84. By removing an outer screw 85 the valve 83 may be adjusted from the exterior of casing 47 to control the flow of gas in by-pass passage 69a.

The adjustable restriction provided by valve 83 effects a pressure differential when gas flows in the by-pass passage, whereby the gas pressure in chamber 53 will be less than that in chamber 54 even when valve 70 is fully open and the latter effects no pressure differential. When valve 57 is fully open the force exerted by gas in chamber 54 on the under side of diaphragm 52 is balanced by the force exerted by gas in chamber 53 on the upper side of the diaphragm and the weight on the latter including the valve 57 and loading means 60. Since the gas pressure in chamber 53 is less than in chamber 54, any increase in gas line pressure will permit diaphragm 52 to move valve 57 toward its closed position to reduce the flow of gas past valve 57. Conversely, when the gas line pressure decreases, the gas pressure on the under side of diaphragm 52 tends to decrease whereby the diaphragm and valve 57 move downward to increase the flow of gas past valve 57. The valve 57 assumes a new position for the increased or reduced gas line pressure when the forces exerted on opposite sides of the diaphragm 52 are balanced. In such new position of valve 57 the gas pressure in chamber 54 is substantially the same as it was before the increase or reduction in gas line pressure took place, whereby gas is delivered to burner 14 at a substantially constant maximum pressure.

When valve 70 is fully open, therefore, the pressure differential in chambers 53 and 54 is effected by valve 83 to provide gas pressure regulation when gas is delivered at a maximum pressure to the burner 14. When valve 70 is partly open, both the valves 70 and 83 effect a pressure differential in the chambers 53 and 54 to provide gas pressure regulation. The valve 83 may be adjusted to any desired position to adjust and limit the pressure on the upper side of diaphragm 52 to a certain percentage of the gas pressure chamber 54, thereby retaining part of the balancing lifting force of diaphragm 52.

In view of the foregoing, it will now be understood that valve 57 is normally controlled by expansible diaphragm 76 which controls the flow of gas in by-pass passage 69 and hence regulates the differential of gas pressures in chambers 53 and 54. By providing the valve 83 in the by-pass passage, as shown in Fig. 3, the control device is also operative to regulate the pressure of gas delivered to burner 14 even when valve

70 is in its full open position, thereby making unnecessary the provision of a separate gas pressure regulator.

While particular embodiments of the improved control device have been shown and described, I do not wish to be limited to the particular arrangement set forth, and I intend in the following claims to cover all modifications which do not depart from the spirit and scope of the invention.

What is claimed is:

1. A control device for a gas burner comprising a valve for controlling flow of gas to a burner, a movable member arranged to be subjected on one side to pressure of gas on the outlet side of said valve and operatively connected to said valve so that said pressure acts toward closure of said valve, a predetermined load acting on said valve toward opening of said valve whereby said valve is constantly maintained in a position such that said pressure balances said load, and means to place additional load on said valve to increase said pressure comprising a conduit for conducting to atmosphere gas from the outlet side of said valve, the other side of said movable member being subjected to pressure of gas in said conduit, said conduit providing a predetermined resistance to gas flow to atmosphere, a relay valve in said conduit, and a thermostat operatively connected to said relay valve so the latter assumes any position between and including its open and closed positions depending upon the temperature to which said thermostat is subjected.

2. A control device as set forth in claim 1 in which there is another adjustable valve in said conduit and adjusted to restrict flow of gas so that pressures cannot equalize on opposite sides of said diaphragm regardless of the operating position of said relay valve.

3. A combined gas pressure regulator and control device for controlling flow of gas and regulating the pressure of such gas delivered to a burner, said combined regulator and control device comprising a casing having an inlet and an outlet, a partition having an opening, a main valve for controlling the opening and hence the flow of gas between the inlet and the outlet, a diaphragm operatively connected to said main valve and at the discharge side of the opening, structure including said diaphragm forming a chamber at the opposite side of said diaphragm from said partition, said casing having a passage to divert to said chamber gas flowing between the inlet and outlet, an auxiliary valve to control flow of gas through said passage to said chamber, said casing having an opening to permit venting of gas from said chamber whereby the latter is substantially at atmospheric pressure when said auxiliary valve is closed, and means responsive to pressure for operating said auxiliary valve so the latter assumes any position between and including its open and closed positions depending upon the pressure to which said last means is subjected.

4. A device for controlling flow of gas to a burner comprising a casing having an inlet and an outlet, a first partition having an opening, a diaphragm, a main valve operatively connected to said diaphragm for controlling the opening and hence the flow of gas between the inlet and the outlet, said diaphragm being located at the discharge side of the opening, a second partition at the opposite side of said diaphragm from said first partition and forming a chamber therewith,

said second partition having an opening, said casing having a passage to divert to said chamber through the last mentioned opening gas flowing between the inlet and the outlet, an auxiliary valve for controlling the opening in said second partition and hence the flow of gas into said chamber, said casing having an opening to permit gas to vent out of said chamber, a first expandible and contractible member at one end of said casing responsive to pressure for operating

10

said auxiliary valve, a second expandible and contractible member at the opposite end of said casing responsive to pressure and arranged to close said main valve irrespective of the control exercised by said first expandible and contractible member over said main valve, and said main valve, auxiliary valve and both of said expandible and contractible members being substantially in alignment within said casing.

SVEN W. E. ANDERSSON.
